UNITED STATES PATENT OFFICE.

BORIS N. NELSON, OF PROVIDENCE, RHODE ISLAND, ASSIGNOR TO D & N MANUFACTURING CO., INC., OF PROVIDENCE, RHODE ISLAND, A CORPORATION OF NEW YORK.

DESIGN FOR A CHARM.

Application filed December 19, 1924. Serial No. 11,744. Term of patent 3½ years.

To all whom it may concern:

Be it known that I, BORIS N. NELSON, a citizen of the United States of America, residing at Providence, county of Providence, State of Rhode Island, have invented a new, Charm, of which the following is a specification, reference being had to the accompanying drawing, forming a part thereof.

an edge view of a charm, illustrating my new design.

I claim:

The ornamental design for a charm, as shown.

BORIS N. NELSON.
